UNITED STATES PATENT OFFICE

2,313,854

DOLL'S EYES

Charles Weltman, Brooklyn, N. Y.

Application July 19, 1941, Serial No. 403,083

3 Claims. (Cl. 46—167)

This invention relates to dolls' eyes and has for its main object to provide eyes for dolls which are movable and which are set in a desired position manually from the outside.

Dolls' eyes which are automatically and mechanically movable have been used in this art, and dolls the eyes of which go into the sleeping or closed position when laid flat, and open again when the doll is placed in an upright position, are old and well known, but they are automatic in operation and the mechanical construction of them is such that they cannot be applied into dolls' heads which are made of soft material and then stuffed.

The main object of this invention is to provide dolls' eyes which are closed from the outside by the player himself, that is, where the player at any time may put the doll in a sleeping or in an awake position.

Another object of this invention is to provide mechanically movable dolls' eyes which may be easily and efficiently set into a stuffed doll head of comparatively soft material.

Still other objects of this invention will be apparent as the specification of the same proceeds, and among others I may mention: to provide dolls' eyes of the character indicated hereinbefore which will be simple in construction, inexpensive to manufacture, easy to apply and to operate manually from the outside, and, preferably, in which no extra element is needed for manually operating the dolls' eyes, but they are operated by a portion thereof, like by the eyelashes.

In the drawing forming a part of this specification and accompanying the same:

Fig. 1 is a front elevation of a doll's head with the novel eyes of my invention installed therein and shown in an open awake position;

Fig. 2 is a diagrammatic front elevation of the same doll's head showing one eye in a closed position and the other eye being closed by the player;

Fig. 3 is a sectional elevation on the line 3—3 of Fig. 1 showing the application of the manually operable doll's eye into the doll's head;

Fig. 4 is a plan view of an element to be installed in the doll's head carrying the mechanical construction for the movable eyes;

Fig. 5 is a fragmentary sectional elevation on the line 5—5 of Fig. 4 showing the construction of the moving element for imitating the closing and opening of the eye;

Fig. 6 is another fragmentary sectional view

to show a preferred construction of the moving portion of the eye;

Fig. 7 indicates a modification in my device whereby both eyes may be moved together simultaneously, and

Fig. 8 shows a blank to be used for the construction indicated in Fig. 6.

Referring now to the drawing more in detail by characters of reference, the numeral 10 indicates the front portion of a hollow doll's head in general, into which is applied my manually operable eye construction, generally indicated by the numeral 11.

The doll's head is shown here as of that construction in which a shell 12 is made of layers of appropriate materials, like textile fabrics, pressed to the shape of the front of the head of the doll and treated on the outside with the necessary paints and colors. The head is then stuffed.

According to my invention, however, before stuffing and closing the head, my movable eye device, generally indicated by the numeral 11 will be secured into the front part of the hollow head, as by the flaps or extensions 13. Said device 11 has a base plate 14 of any appropriate material, like cardboard, on which may be secured two elongated metal plates 15, the longitudinal edges thereof being inwardly turned, as at 16, to form guide channels for the sliding plates 17 which are the members shaped to imitate the appearance of the doll's eyes.

Each of said sliding plate members 17 may have a somewhat curved protruding ridge 18 in the center thereof which is provided to imitate the eyelashes. It also has an imitation iris 19 painted thereon below said eyelashes 18 in the color desired for the doll's eye, usually blue. The lower half 20 of the sliding plate 17 may be painted white to imitate the white of the eye, while the upper half is colored to imitate the front of the eyelids when they are closed. Base plate 14 of my movable eye device will be arranged in the hollow head of the doll in such a manner that the eyelashes 18 will protrude to the front of the face of the doll through the eye openings 22.

Normally, the doll's face appears as shown in Fig. 1 with the eyes wide open, that is, the eyelash imitations being pushed upwardly to the upper ends of the eye openings 22. When it is desired to place the doll's eyes into sleeping position, the eyelash imitations 18 may be caught between the thumb and the forefinger of the player and pulled downwardly, as indicated in Fig. 2. Performing this downward pulling operation on

both eyes, the doll will appear as asleep, while doing the reverse operation on the doll's eyes, that is, pulling the eyelash imitations 18 upwardly, will cause the plate 17 to slide in an upward direction and will expose the lower half 20 of the sliding plate 17 through the eye openings 29 and the iris 19 therein, thereby giving the effect of the eyes being open, as in Fig. 1.

In such a manner, the player, that is, usually a small girl owning the doll, may put the doll to sleep or to an awake position at her desire at any time without having to place the doll into different positions, as is the case with the present mechanical automatically operating movable doll's eyes.

In Fig. 4 the open position of the eye imitation members is shown with full lines, while the position when the doll's eyes are closed is indicated by the dotted lines.

A preferred method of forming the sliding plate 17 with its protruding eyelash imitation 18 is indicated in Figs. 6 and 8. In this form the plate 17 and its eyelash imitation 18 are formed of one piece of sheet metal or similar material, which first is cut into the blank 17a shown in Fig. 8. The blank is folded on the three lines 24, 25 and 26, the center portion 27 thereof being doubled and caused to perpendicularly rise from the plane of the blank 17a and thereby form the eyelash imitation 18. In pressing the slide plates 17 from the blank 17a, they may be somewhat curved as shown in Fig. 5 to better imitate the eyeballs, and the eyelashes 18 may also be curved somewhat downwardly at the two ends, as indicated in Figs. 1, 2 and 4.

The eyelash imitations 18 may have eyelashes 18a secured thereon to make it appear more natural, or they may otherwise be painted and prepared to imitate eyelashes and they may be

made of other material than metal or may be coated with rubber to prevent possible injury to the fingers of the child playing with the doll.

In Fig. 7 I indicate in a diagrammatical manner that a rigid member 28 may connect the two sliding plates 17 and with such a construction, the moving of one eye will cause the other eye to move simultaneously and in a similar manner, as will be obvious.

What I claim as new, is:

1. In a doll's head, having a hollow face portion and openings therein for the eyes, a separate base plate secured in said head to the rear of each eye opening and spaced apart from said face, a 15 slidable element on each base plate having adjacent portions in the direction of the sliding thereof imitating an open and a closed eye, respectively, a rigid imitation eyelash projecting from each sliding element through the eye opening to the front of the face, said sliding element being adapted to be moved by said eyelash in one or in the other direction to expose the eye imitation through said eye opening in a closed or in an open position, respectively.

2. In a doll's head, as set forth in claim 1, said sliding element being adapted to remain in its respective position showing the eye imitation in a closed or in an open condition permanently until changed.

3. In a doll's head, as set forth in claim 1, said slidable element being in the form of a plate having a middle portion adapted to be folded doubled in its center and to be raised in its doubled condition perpendicularly to said plate upon a perpendicular bending of its ends in said plate, said perpendicularly rising doubled folded projection in said slidable plate forming said imitation eyelashes.

CHARLES WELTMAN.
